UNITED STATES PATENT OFFICE.

ALFRED H. WADEWITZ, OF RACINE, WISCONSIN.

CHASE-LOCK.

1,078,594.

Specification of Letters Patent. Patented Nov. 11, 1913.

Application filed January 23, 1913. Serial No. 743,792.

To all whom it may concern:

Be it known that I, ALFRED H. WADEWITZ, a citizen of the United States, residing at 817 Hamilton street, in the city of Racine, State of Wisconsin, have invented a new and useful Chase-Lock.

The invention relates to printing presses, and more particularly to the class of false chases for flat bed printing presses.

10 The primary object of the invention is the provision of a false chase in which wood furniture and quoins ordinarily used in blocking and locking type chases are entirely dispensed with, as the said type chases 15 can be securely mounted and fastened in proper position on the flat bed of the printing press irrespective of the shape and size of the form.

20 Another object of the invention is the provision of a false chase in which the type chase will be held on three of its sides so that there will be no possibility of displacement of the same during the working of the press, yet the type chase can be readily and 25 quickly adjusted when upon the flat bed of the said press.

25 A further object of the invention is the provision of a false chase which is simple in construction, readily and easily mounted 30 and adjusted on the bed of the printing press, and also one which is strong, durable, thoroughly reliable and efficient in its purpose, and inexpensive in manufacture.

35 With these and other objects in view, the invention consists in the construction, combination and arrangement of parts as will be hereinafter more fully described, illustrated in the accompanying drawing, and pointed out in the claims hereunto appended.

40 In the drawing: Figure 1 is a fragmentary plan view of a flat bed printing press with the type chase mounted thereon, and the false chase constructed in accordance 45 with the invention in operative position. Fig. 2 is a sectional view on the line 2—2 of Fig. 1. Fig. 3 is a perspective view of one of the holding dogs. Fig. 4 is a perspective view of one of the side bars adapted to co- 50 operate with the holding dogs.

Similar reference characters indicate corresponding parts throughout the several views in the drawing.

55 Referring to the drawings by numerals, 5 designates generally the flat bed of a printing press of the ordinary well-known type

on the upper face of which are fixed as usual side bars 6, which are ordinarily known as brayers, the same being fastened thereto in any suitable manner, while arranged between and secured to the upper face of the said bed nearest the end of the cylinder of the printing press is a cross bar 7. At the opposite end of the bed 5 and rising therefrom are spaced lugs 8 provided with adjusting screws 9 working against a bar 10 which serves as a contacting strip for one end of a type chase 11 of the usual construction.

The false chase comprises a pair of bars 12, which are arranged against the inner side of the bars 6 so as to lie parallel therewith, the inner edges of the bars 12 being formed with spaced semicircular-shaped notches 13 throughout a greater portion of their length, while each bar at one end is provided with an out-turned ear 14 disposed against one end edge of the side bar 6 adjacent thereto. The ears 14 have threaded therein set screws 15, which enable the bars 12 to be adjusted longitudinally upon the bed of the printing press. Clamping dogs 16 are formed with curved fingers 17 and 18 respectively, the fingers 17 being designed to engage the upper or inner end of the type chase and the fingers 18 being designed to engage the two sides of the type chase which run parallel to the sides of the press; the engaging of the said fingers 17 and 18 with the said ends and sides of the type chase being for the purpose of securely holding the said type chase on the bed of the printing press. The dogs are formed with nibs 19, which engage in the notches 13 in bars 12, whereby said dogs will be held in 95 adjusted position for clamping the type chase in a manner as shown in Fig. 1 of the drawing.

When it is desired to tighten the type chase 11 when engaged by the dogs, the adjusting screws 9 in the ears 8 are turned, thereby locking the said chase upon the flat bed of the printing press without requiring the use of ordinary wood furniture or quoins.

105 It is clearly apparent that the dogs may be positioned with respect to each other to accommodate type chases of different size, the dogs being made in different sizes to meet different sizes of chases and presses.

110 From the foregoing description, taken in connection with the accompanying drawing,

it is thought that the construction and operation of the invention will be clearly understood, and therefore a more extended explanation has been omitted.

5 The invention herein described and shown in the accompanying drawing, while somewhat similar, differs in several material respects from the invention for which I was heretofore granted a Patent Number 10 1,048,241, which issued on December 24, 1912, as will appear by a comparison of the specifications and drawings, namely, in the elimination of the cross-bar (numbered 16 in the specification and drawing of the former invention), and the replacing of the holding dogs (numbered 18 in the specification and drawing of the former invention) by dogs of a different shape and size so designed as to engage with and fit directly into the notches 13 of the bars 12, as appears by the accompanying drawing, (said latter dogs being numbered 16 in this specification and in the accompanying drawing). The advantage of this invention is 15 that, with dogs varying in length and size depending upon the size of the chase and press, the chase lock herein described will

fit practically any press, and firmly hold the type chase in place.

I claim:

1. The combination with the flat bed of a printing press having spaced parallel side bars fixed to and rising from said bed, and notched bars arranged against the inner sides of said parallel side bars and resting upon said bed; of clamping dogs resting upon said bed and adapted and arranged so as to adjustably engage the said notched bars and the inner end and sides of a type chase, substantially as described. 30

2. The combination with the flat bed of a printing press having spaced parallel side bars fixed to and rising from said bed, and notched bars arranged against the inner edges of said side bars and supported upon the bed, of clamping dogs adapted to engage both the end and sides of a type chase and adjustably engaging the notched bars, and means on the outer side of said type chase to secure the same upon the flat bed. 45

ALFRED H. WADEWITZ.
